(57) CLAIM

The ornamental design for an apron with attachable hot pads, as shown and described.

DESCRIPTION

FIG. 1 is a perspective view of an apron with attachable hot pads showing my new design;

FIG. 2 is a front elevational view thereof;

FIG. 3 is a front elevational view thereof, the hot pads shown removed from the apron;

FIG. 4 is a rear elevational view thereof;

FIG. 5 is a side elevational view thereof;

FIG. 6 is a top plan view thereof;

FIG. 7 is a bottom plan view thereof;

FIG. 8 is a front elevational view of a single hot pad, the apron shown removed for ease of illustration;

FIG. 9 is a rear elevational view thereof, the apron shown removed for ease of illustration;

FIG. 10 is a side elevational view thereof, the apron shown removed for ease of illustration; and,

FIG. 11 is a top plan view thereof; the apron shown removed for ease of illustration.
